FLATIRON HOLDER

Chester D. Stanley, Akron, Ohio, assignor, by direct and mesne assignments, to The Wil-Stan Products Company, Akron, Ohio, a corporation of Ohio

Application December 13, 1945, Serial No. 634,851

3 Claims. (Cl. 248—117.1)

1

This invention relates to flatiron holders, and more especially it relates to a holder adapted to be suspended from a wall structure or the like for storing a flatiron during periods when it is not in service.

The chief objects of the invention are to provide an improved structure of the character mentioned that positively retains the flatiron in place; that provides in an efficient manner for preventing the scorching of the wall when the flatiron is inserted in the holder while hot; to provide means on the holder about which the electric cord of the iron may be looped without kinking or sharp flexure, including means for retaining the plug on the end of the cord in fixed position; and in general to provide a flatiron holder of relatively few parts that readily may be manufactured at relatively low cost. Other objects will be manifest as the description proceeds.

Of the accompanying drawing:

Fig. 1 is a front elevation of a flatiron holder embodying the invention, the position of a flatiron therein being indicated in dot and dash lines;

Fig. 2 is a side elevation of the structure shown in Fig. 1;

Fig. 3 is a section on line 3—3 of Fig. 1, on a larger scale; and

Fig. 4 is a section on line 4—4 of Fig. 1.

Referring to the drawing, it will be seen that the holder comprises a mounting plate 10 that is composed of sheet metal, such as aluminum, and which is adapted to be attached to a wall structure or the like by a nail or other suitable means (not shown) that extends through an aperture 11 in the upper extremity of the plate. The plate 10 as shown is of general elliptical contour, and is formed with a rearwardly extending marginal flange 12 of suitable height to hold the plate in suitable spaced relation to the wall on which it is mounted. It will be obvious that the contour of the plate 10 may be of different shape if desired.

In the lower half of the plate 10 there is a symmetrically arranged opening or cut-away portion 14 that has the general contour or outline of a conventional electric flatiron having its pointed forward end or nose directed downwardly. Preferably said opening is appreciably larger in area than the flat working face of the flatiron. At the margin of the opening 14, at each side of the pointed lower extremity thereof, are respective forwardly extending longitudinally and transversely arcuate flanges or wings 15, 15 that constitute the sole supporting elements of a flat-

2

iron when mounted in the holder, at which time the said wings embrace the sides and top of the nose portion of the flatiron. Preferably the plate 10 and wings 15 are a one-piece structure, the wings being part of the material struck out from the opening 14.

Mounted upon the back of the plate 10 at the lower end portion thereof is thermal insulation that extends through the opening 14 so as to be flush with the front face of the plate. Preferably said thermal insulation is composed of non-combustible material such as asbestos, which is in sheet form. Two sheets 17, 17 of the asbestos sheeting are employed, which sheets are maintained in parallel, spaced relation to each other by intervening locally positioned spacer members 18, 18 of the same material, whereby air-spaces 19 are provided between the sheets 17. A suitable adhesive is employed for bonding the asbestos sheeting to the spacer members 18 and to the plate 10, although other means for uniting said parts may be utilized if desired. The thermal insulation does not extend rearwardly beyond the margin of the plate-flange 12.

25 Numerous makes of present day electric flatirons have conductor cords that are permanently connected at one end to the irons, such an iron being indicated at 22, Figs. 1 and 2, whereof 23 is the conductor cord and 24 is a conventional plug on the free end of said cord. To preserve the cord from flexure and kinks, and to provide for neat storage thereof, means is provided on the holder for receiving the cord when the iron is reposing in the holder. To this end a 30 pair of prongs 25, 25 are struck out from the plate 10, in the upper part thereof, which prongs are symmetrically disposed on opposite sides of the vertical centerline of the holder. The prongs 25 project forwardly, and are somewhat divergent in the direction of their free ends, as shown in Fig. 3. The prongs are bent transversely to concavo-convex shape with the concave sides confronting each other, the arrangement being such that the iron-cord 23 may be looped about the prongs in the manner shown in the drawing, and engage only the smooth convex sides thereof, whereby excessive wear on the cord is obviated.

35 Below the prongs 25 the plate 10 is formed with two, small, adjacent slots 27, 27 that are adapted to receive the respective contact fingers or springs of the plug 24, and thereby to support the latter in determinate position, where it is easily accessible for insertion or removal.

The invention is of attractive appearance and of simple construction. It provides a conveni-

3

ent and safe receptacle for a flatiron that is hot from recent use, and achieves the other objects set out in the foregoing statement of objects.

Modification may be resorted to without departing from the spirit of the invention, or the scope thereof as defined by the appended claims.

What is claimed is:

1. A flatiron holder of the character described comprising a vertically arranged metal plate formed near its bottom with an opening therein having the general shape of the outline of a flatiron having a downwardly pointed nose, a heat-insulating structure in said opening flush with the front face of the plate, means on the 10 plate for supporting a flatiron in contact with said heat-insulating structure, and a pair of prongs projecting from the front of the plate, above said opening, in position to have the conductor cord of a flatiron looped thereabout when 20 the iron is supported in the holder.

2. A combination as defined in claim 1 whereof the plate and prongs are a one-piece structure, the prongs being struck out from the plate, and

bent to concavo-convex shape with the concave sides in confronting relation to provide rounded convex surfaces for contact with the cord.

3. A combination as defined in claim 1 including two short, adjacent slots in the plate below the prongs for receiving the contact fingers of a plug on the end of the conductor cord.
